PATCH POCKET AND METHOD OF MAKING
SAMEGeorge W. Bayless, Los Angeles, Calif., assignor to
Tobias Kotzin, Los Angeles, Calif.

Application August 13, 1946, Serial No. 690,224

6 Claims. (Cl. 2—247)

1

This invention relates to pockets commonly used on various garments, such as trousers, shirts, jackets, dresses, and the like; more particularly, it relates to pockets of the type sometimes known as patch pockets, and to a method of making them.

It is known to form pockets on garments of various types by appropriately attaching a suitable piece of fabric on the outside of the garment. It is an object of this invention to provide an improved pocket of this type.

It is another object of this invention to provide a patch pocket in which there is no raw edge along the opening of the pocket; and, further, to provide such a pocket free of exposed overlocking or other stitching along the opening.

It is still another object of this invention to provide a novel and improved method of making such a pocket.

It is still another object of this invention to provide a novel and improved method of forming a pocket in which the edge of the patch forming the pocket has oppositely and upwardly inclined edge portions meeting centrally of the edge.

This invention possesses many other advantages, and has other objects which may be made more clearly apparent from a consideration of one embodiment of the invention. For this purpose there is shown a form in the drawings accompanying and forming part of the present specification. The form will now be described in detail illustrating the general principles of the invention; but it is to be understood that this detailed description is not to be taken in a limiting sense, since the scope of this invention is best defined by the appended claims.

In the drawing:

Figure 1 shows the outline of a piece of fabric for forming the pocket of the invention;

Figs. 2, 3, and 4 show successive forming operations on the piece of Fig. 1;

Figs. 5 and 6 are detail sections, taken as indicated by correspondingly numbered lines on Fig. 4;

Fig. 7 shows the piece upon completion of further steps;

Fig. 8 is a detail section, taken as indicated by line 8—8 on Fig. 7; and

Fig. 9 shows the finished pocket.

Referring to Fig. 9 of the drawing, a fragment of a garment, which is shown, by way of example, as a pair of trousers, is indicated by 1, and a pocket embodying the features of the invention is indicated by 2. This pocket is formed by an appropriately shaped piece of fabric 3, joined

2

at its side and bottom edges to the material of the garment by conventional stitching 4. The upper edge 5 of the piece 3 is unattached, providing the pocket opening. This opening may be arranged, if desired, to be closed by means of a button 6 on the garment and a cooperating buttonhole 7 in the piece 3.

To impart a pleasing appearance to the garment, as well as to provide satisfactory additional depth to the pocket, the edge 5 comprises oppositely and upwardly inclined portions 5—a and 5—b, meeting centrally of the edge 5. Thus, the central portion of the pocket has a greater depth than the edge portions. Furthermore, the edge 5 is so formed as to avoid a raw edge of the fabric 3, and also is free of exposed stitching, overlocking, or the like.

The manner of forming the pocket fabric 3 will now be described. The fabric is first cut to a pattern, as shown in Fig. 1, the bottom edge 8 and the side edges 9 conforming substantially to the shape of the finished pocket 2. The piece 3 has an extension 10 beyond the body portion 11 between the sides 9, the termination of the sides 20 being indicated at points 12 and 13 by appropriate marks, such as small cuts or notches. The sides of the extension 10 diverge outwardly from the marks 12 and 13, the upper edge surface 14 of the extension having portions 14—a and 14—b inclining upwardly from each side 9 to a high point 15 intermediate the sides 9. This point 15 may be an apex formed by the meeting of sides 14—a and 14—b, or it may comprise the mid-point of an arc joining the sides. In either case, a cut 16, 25 bisecting the angle, or arc if a rounded top is desired, included between the upper edge surfaces 14—a and 14—b, extends inwardly from the point 15, and appropriate marks 17 and 18 are provided on each side of the cut 16, being 30 equally spaced therefrom.

After the fabric is cut in accordance with Fig. 1, the fabric between the cut 16 and one of the marks, as 17, is overlapped to bring the adjacent edge of the cut 16 to the mark 17, as shown in Fig. 2, forming a fold 19, the right-hand edge of the cut 16, after folding, being indicated by 16—a. With the material suitably held in folded condition, the left-hand edge 16—b of the cut in Fig. 2 is brought over to mark 17, as shown in Fig. 3. 35 In this step, the edges 16—a and 16—b become coincident. The points 17 and 18 are so positioned with respect to the cut 16 that this movement serves to position the fold 19 in a more nearly vertical position. The top edge is now 40 formed by sides that are more nearly flat than

that in the unoverlapped step of Fig. 1. The top edge of the extension 10 is then provided with serging or overlocking 20 (Fig. 4) to retain the material overlapped. This overlapping results in a substantial fullness of the fabric below the cut 16, as indicated at 21 in Fig. 4.

After the overlocking, the extension 10 is folded over about the points 12 and 13 in a direction to enclose cut edges 16-a and 16-b between the extension 10 and the body portion 11. The fullness 21 of the fabric mentioned above permits the fold occurring along a straight line between the points 12 and 13. Additionally, the fullness 21 acts to prevent the upper edge surfaces 14-a and 14-b maintaining their relative inclination (Fig. 4) after the folding.

The downward fold of the material results automatically in the formation of a crest or high point 23. It is at this point that the fullness 21 (Fig. 4) occurs, and the top edge 5 must form this crest in order to take up the fullness. At the same time, the overlocked edge 14 falls substantially along a straight line 22.

It is desirable to secure the folded extension 10 at its mid-point to the body portion 11 of the pocket fabric 3, as by stitching 24. This stitching 24 may be conveniently the buttonhole stitching provided for the buttonhole 7.

The fabric piece 3, after completion, may be secured to the garment 1 in a conventional manner. Thus, the bottom and side edges 8 and 9 may be turned in about the dotted lines 25 in Fig. 5, and the piece 3 blindstitched to the garment 1.

The inventor claims:

1. In a pocket construction for a garment: a fabric member having a first fold substantially central of the top edge and extending downwardly from the top edge, said member also having a portion overlying said first fold at the top edge whereby a fullness results adjacent the center portion of the top edge; said member also having another fold across the member transverse to the first fold to provide a crest or high point at the fold where the fullness occurs.

2. In a pocket construction for a garment: a member forming the pocket exterior, which member, when flat, has an arched upper edge and a cut extending downwardly from the top central point of said edge; one side of the cut being folded over to form a triangular double layer having its apex at the bottom of the cut, the other side of the cut being placed over the said double layer to form a third layer; thus having its arch reduced and

there being a fullness adjacent the said multiple layer; and the top edge being folded transversely to form an arch at the folded edge, the fullness being absorbed by the said arch.

3. The method of making a pocket which comprises forming a fabric body with the side and bottom edges conforming substantially to the desired configuration of the finished pocket, said body having an upper extension with oppositely inclined meeting edge portions overlapping the mid portion of said extension to reduce the inclination of said portions, folding said upper extension over so that said edge is straight and the folded edge has inclined meeting portions, and securing said folded extension to said body.

4. The method of making a pocket which includes: providing a fabric piece having an edge with oppositely inclined portions meeting at a point, overlapping said piece adjacent said point for a limited distance from the point to reduce the inclination of said edge portions, folding said piece in the direction in which the edge extends, straightening said edge to form a fold having oppositely inclined portions, and securing said piece in folded condition.

5. The method of forming a pocket which comprises folding a fabric piece along a fold extending substantially centrally of the top and downwardly to provide fullness adjacent the center portion; and then folding the top portion transversely to the first fold to cause said fullness to form a crest or high point.

6. The method of forming a pocket which comprises folding a fabric piece along a fold extending substantially centrally of the top and downwardly to provide fullness adjacent the center portion; then folding the top portion transversely to the first fold to cause said fullness to form a crest or high point; and securing said piece in position on a garment, leaving said lateral fold unattached to form the pocket opening.
